UNITED STATES PATENT OFFICE.

GEORGE A. AMSDEN, OF LITTLETON, MASSACHUSETTS, ASSIGNOR TO THE LAMSON COMPANY, (FORMERLY LAMSON CONSOLIDATED STORE SERVICE COMPANY,) OF BOSTON, MASSACHUSETTS, A CORPORATION OF NEW JERSEY.

CABLE-CARRIER APPARATUS.

1,108,823.

Specification of Letters Patent. Patented Aug. 25, 1914.

Application filed November 23, 1912. Serial No. 733,115.

To all whom it may concern:

Be it known that I, GEORGE A. AMSDEN, of Littleton, in the county of Middlesex and State of Massachusetts, have invented certain new and useful Improvements in Cable-Carrier Apparatus, of which the following is a specification.

My invention relates to improvements in cable carrier apparatus and its object is to provide means whereby carriers of the general type shown and described in my United States Letters Patent No. 1,101,518 may traverse the bends and pass the idlers and pulleys supporting the cable without danger of throwing the carriers out of engagement with the cable and without necessitating the changing of the position of the carrier.

In the accompanying drawings is illustrated a construction embodying my invention in which—

Figure 1 is an elevation of a 90 degree bend comprising the corner of a cable carrier apparatus and showing a carrier traversing the same. Fig. 2 is an end view of Fig. 1 showing the track broken away on line 2—2 looking in the direction indicated by the arrow. Fig. 3 is an enlarged view of a portion of one of the idlers or supporting pulleys showing the position of the cable and carrier while traversing the same. Fig. 4 is a sectional view through the center of one of the idlers.

Like characters of reference refer to like parts throughout the several views.

35 A and B represent respectively the out-going and in-going tracks upon which the carrier is adapted to travel. The tracks B at the bend are supported by the corner brackets D in which is journaled the idler or supporting pulley E which supports the in-going portion of the driving cable C. The tracks A are supported at the bend by the corner bracket F in which is journaled the supporting pulley or idler G which supports the out-going portion of the driving cable C. The brackets D and F are supported in relative positions by the bent rod or shaft H which forms a fixed shaft upon which the idlers E and G rotate. The idlers are constructed with a central peripheral flange J which divides the pulley into two separate grooves P and L, see Figs. 3 and 4, one of which the cable normally traverses.

When a carrier is being transmitted by

the cable and arrives at one of the turns or bends as shown in Fig. 1, the jaws N and K which comprise the spring clamp of the carrier, are engaged by the sides of the grooves P and L respectively, retaining the cable C within said clamp and causing the cable to ride upon the peripheral flange J which also prevents the cable from being thrown out of the grip of the clamp, see Fig. 3. After the carrier passes the idlers and rounds the bend, the cable drops back to its normal position in either of the grooves P and L.

I do not limit myself to the construction herein shown as the peripheral flange J may be dispensed with forming a single groove pulley and leaving the wedging action of the jaws N and K within the groove of the pulley to enable the carrier to make the turn without dropping the cable.

Having thus described my invention and set forth a construction embodying the same what I claim as new and desire to secure by Letters Patent of the United States is:

1. In a cable carrier apparatus, a track or way, an actuating cable for driving carriers along said track or way, a carrier having a clamp comprising opposing jaws one at least of which is resilient; said jaws adapted to be resiliently clipped onto said cable, pulleys for supporting said cable, and means for momentarily locking the jaws of said clamp to prevent the resilient opening thereof and consequent disengagement of said cable therefrom when the carrier passes said pulleys.

2. In a cable carrier apparatus, a track or way, a carrier adapted to travel on said track or way, a cable for driving said carrier, a spring clamp comprising opposing jaws, one at least of which is resilient, located on said carrier and adapted to be clipped into engagement with said cable, and a pulley located at a bend and adapted to support said cable, said pulley carrying a central peripheral flange thereon adapted to hold said cable securely between the jaws of said clamp when said carrier is passing said bend.

3. Cable carrier apparatus comprising a track, a carrier to travel thereon, a cable for driving said carrier, said carrier having means to engage said cable, a pulley about which said cable normally passes and around which said carrier is drawn by said

cable, and means, independent of the carrier and its cable engaging means, to directly engage said cable and aid in retaining it in place in said cable engaging means 5 when said cable is pulled away from the surface of said pulley by the passage of said carrier therearound.

4. Cable carrier apparatus comprising a track, a carrier to travel thereon, a cable 10 for driving said carrier, said carrier having means to engage said cable, a pulley about which said cable normally passes and around which said carrier is drawn by said cable, means, carried by said pulley for directly engaging said cable and for also engaging the cable engaging means of said carrier, to retain said cable in place in said cable engaging means when the cable is pulled away from the surface of the pulley 20 by the passage of the carrier therearound.

5. In a cable carrier apparatus, a track or way, a carrier adapted to travel on said track or way, a cable for driving said carrier, a spring clamp comprising opposing jaws, one at least of which is resilient, located on said carrier and adapted to engage said cable, and pulleys or idlers located at the bends in said way and adapted to support said cable, each of said pulleys or idlers 25 carrying a central peripheral flange thereon adapted to hold said cable securely between the jaws of said clamp when said carrier is passing said bends, each of said pulleys also being provided with flanges to engage the 30 jaws of the carrier and hold them clamped on the cable when said carrier is passing around a pulley.

6. Cable carrier apparatus comprising a track, a carrier to travel thereon, a cable for

driving said carrier, said carrier having 40 means to engage said cable, a pulley about which said cable normally passes and around which said carrier is drawn by said cable, and means, independent of the carrier and its cable engaging means, to directly engage said cable and aid in retaining it in place in said cable engaging means when said cable is pulled away from the surface of said pulley by the passage of said carrier therearound, said pulley having 45 a flange to engage a part of said cable engaging means when said carrier is passing around said pulley and adapted to co-act with said independent means to also aid in retaining said cable in place in said cable 50 engaging means when the carrier is passing around said pulley.

7. Cable carrier apparatus comprising a track, a carrier to travel thereon, a cable for driving said carrier, said carrier having a 60 grip to engage said cable, means, independent of said carrier and its grip, to directly engage said cable substantially at the point where it is engaged by said grip when said carrier is traversing a bend in said track, 65 and co-acting means to engage at least a part of said grip at such times, said last two mentioned means adapted to prevent said cable from springing out of said grip at said bend.

In testimony whereof, I have signed my name to this application in the presence of two subscribing witnesses, this 17th day of Sept. 1912.

GEORGE A. AMSDEN.
